[57] CLAIM

The ornamental design for our vehicle marker light, as shown and described hereinbefore.

DESCRIPTION

FIG. 1 is a perspective view of our vehicle marker light shown obliquely from one side, slightly from the front end and slightly from above;

FIG. 2 is a perspective view of our vehicle marker light, shown obliquely from one side, from the rear side and slightly from below;

FIG. 3 is a planar view showing our vehicle marker light from below;

FIG. 4 is a planar side view of our vehicle marker light, the opposite side being a reverse image thereof;

FIG. 5 is a planar view of our vehicle marker light from above;

FIG. 6 is a planar view showing our vehicle marker light from the front end thereof; and,

FIG. 7 is a planar view showing our vehicle marker light from the rear end.

FIG. 1

FIG. 2

FIG. 3

FIG. 6

FIG. 4
